SHIFTABLE FLEXIBLE SHEET SECURING DEVICE

Erich Gericke, Berlin-Steglitz, Germany

Application April 24, 1952, Serial No. 284,057

Claims priority, application Germany April 26, 1951

8 Claims. (Cl. 101—415.1)

The invention relates to a fixing device for metal sheets, in which the metal sheet that is fixed to the clamping strip is displaceable on the form cylinder.

In order that it should be possible to obtain an accurate fit and an accurate adjustment, the metal sheet must be displaceable in every direction, i.e., also in an oblique direction. The displacement of the metal sheet in the direction or in the direction opposite to the direction of running of the form cylinder is usually effected by rotating the form cylinder on its axle. In the known devices, for the purpose of transverse and oblique setting, screws or other clamping members have to be loosened and, in most cases, even the metal sheet, which does not have to be shifted, has to be loosened in order that it should be possible to displace the metal sheet while being kept free from folds. The tightening of the screws must then be effected by feel; this, however, requires a great deal of experience and, frequently, a bending of the metal sheet takes place.

The invention provides a fixing device in which the metal sheet is loosened at its two ends by the clamping screws in such a manner that each end can be shifted independently of the other. On re-tightening the clamping screw, the metal sheet is, owing to its two-point suspension in the desired position, clamped on the cylinder free from folds and bends, thus straightening itself.

The characteristic feature of the invention consists in mounting each of the two clamping strips in a swivel bearing, which is displaceable preferably in the direction of the axis of the form cylinder and about which the corresponding clamping strip is rockable in a plane in which the clamping edge of the form cylinder is located.

The invention is represented by way of example by the accompanying drawings, of which:

Figure 1 is a section through the form cylinder of an offset machine with a metal sheet fixed thereon;

Figure 2 is an elevation of the clamping device represented in Figure 1, as seen from the right-hand side of Figure 1, the right-hand end of the metal sheet being displaced downwards;

Figure 3 is a diagrammatic representation of a normally fixed metal sheet;

Figure 4 is a diagrammatic representation of a metal sheet in which the two ends have been displaced in opposite directions; and

Figure 5 is a diagrammatic representation of a metal sheet in which the two ends are displaced to the same side.

The clamping device is, as usual, accommodated in the gap of the offset cylinder 1. The metal sheet 2 is, at its front edge 3 and at its rear edge 4, held by two hook strips or clamping strips 5 and 6 which lie slidingly on the two supporting rails 7 and 8. The hook strips 5 and 6 are of angular shape. The strips 5 and 6 are mounted at their mid-points by swivel bearings in the form of ball-and-socket joints 9 and 10 respectively, of which the swivel bearing 9 is mounted on a lever 11, and a swivel bearing 10 is mounted on a lever 12. The

2

lever 11 is mounted on a sliding piece 14 by a pin 13 whilst the lever 12 is mounted on a sliding piece 16 by a pin 15. In addition, the lever 11 has a pin 17 and the lever 12 has a pin 18. The pins 17 and 18 are connected together by a spring 19, so that the ends of the levers 11 and 12 are pressed against a clamping screw 20 by the action of this spring 19.

By tightening the screw 20, the levers 11 and 12 are rotated about their pins 13 and 15, and their ball-and-socket joints 9 and 10 press against the hook strips 5 and 6, so that the metal sheet is applied to the surface of the cylinder and is clamped firmly thereon.

The sliding piece 14 is guided on the pins 21 and 22 which engage in the slots 23 and 24 in the sliding piece. The displacement of the sliding piece 14 is effected by an eccentric 25. The sliding piece 16 is guided on pins 26 and 27 which engage in the slots 28 and 29 in the sliding piece. The displacement of the sliding piece 16 is effected by an eccentric 30. When the eccentrics 25 and 30 are rotated, the bearing positions of the ball-and-socket joints 9 and 10 are displaced and the hook strips are set obliquely in accordance with the lateral displacement of the sliding pieces 14 and 16. After tightening the clamping screw 20, the metal sheet 2 lies clamped on the form cylinder.

On the adjustment as shown in Figure 2, the ball-and-socket joint 10 has been displaced towards the left by the device hereinbefore described, so that an oblique position, twisted to the right, of the metal sheet 2 is produced.

Figure 3 represents the normal position of the metal sheet, in which the ball-and-socket joints 9 and 10 lie in a plane, which passes through the clamping screw 20, perpendicular to the cylinder 1.

In Figure 4, the ball-and-socket joint 10 has been displaced to the right but the ball-and-socket joint 9 has been displaced to the left, so that an obliquely twisted position of the metal sheet 2 is produced.

In Figure 5, the two ball-and-socket joints 9 and 10 have been displaced to the left by the eccentrics 25 and 30, so that the metal sheet has been moved uniformly over the cylinder 1.

In order to shift the metal sheet 2, the clamping screw 20 is loosened, the eccentrics 25 and 30 are shifted until the desired position of the metal sheet 2 is reached, and the clamping screw 20 is again tightened, so that in this way the metal sheet is tightly applied to the cylinder 1.

What I claim is:

1. A device for fixing metal sheets on offset machines, comprising two clamping strips adapted to have a metal sheet fixed thereto, said metal sheet being displaceable on the form cylinder by shifting said clamping strips, two displaceable swivel bearings in which said clamping strips are respectively mounted and about which said clamping strips are respectively rockable in a plane containing the clamping edge of the form cylinder, two sliding plates and eccentrics for displacing said sliding plates, said swivel bearings being respectively arranged on said sliding plates.

2. A device for fixing metal sheets on offset machines, comprising two clamping strips adapted to have a metal sheet fixed thereto, said metal sheet being displaceable on the form cylinder by shifting said clamping strips, two displaceable swivel bearings in which said clamping strips are respectively mounted and about which said clamping strips are respectively rockable in a plane containing the clamping edge of the form cylinder, two sliding plates and eccentrics for displacing said sliding plates, said swivel bearings being respectively arranged on said sliding plates and being movable on said sliding plate for fixing said metal sheet.

3. A device for fixing metal sheets on offset machines,

comprising two clamping strips adapted to have a metal sheet fixed thereto, said metal sheet being displaceable on the form cylinder by shifting said clamping strips, two displaceable swivel bearings in which said clamping strips are respectively mounted and about which said clamping strips are respectively rockable in a plane containing the clamping edge of the form cylinder, two swivel plates on which said swivel bearings are respectively arranged, two sliding plates respectively hinged to said swivel plates, eccentrics for displacing said sliding plates, and, arranged on the form cylinder, clamping means for regulating the shifting of said swivel plates and the clamping of said metal sheet caused by said shifting.

4. A device for fixing metal sheets on offset machines, comprising two clamping strips adapted to have a metal sheet fixed thereto, said metal sheet being displaceable on the form cylinder by shifting said clamping strips, two displaceable swivel bearings in which said clamping strips are respectively mounted and about which said clamping strips are respectively rockable in a plane containing the clamping edge of the form cylinder, two swivel plates on which said swivel bearings are respectively arranged, two sliding plates respectively hinged to said swivel plates, eccentrics for displacing said sliding plates, and, arranged on the form cylinder, a clamping device for regulating the shifting of said swivel plates and the clamping of said metal sheet caused by said shifting, said clamping device being common to said two swivel bearings.

5. A device for fixing metal sheets on offset machines, comprising two clamping strips adapted to have a metal sheet fixed thereto, said metal sheet being displaceable on the form cylinder by shifting said clamping strips, two displaceable swivel bearings in which said clamping strips are respectively mounted and about which said clamping strips are respectively rockable in a plane containing the clamping edge of the form cylinder, two swivel plates on which said swivel bearings are respectively arranged, two sliding plates respectively hinged to said swivel plates, eccentrics for displacing said sliding plates, and, arranged on the form cylinder, a clamping device for regulating the shifting of said swivel plates and the clamping of said metal sheet caused by said shifting, said clamping device being common to said two swivel plates.

6. A device for fixing metal sheets on offset machines, comprising two clamping strips adapted to have a metal sheet fixed thereto, said metal sheet being displaceable on the form cylinder by shifting said clamping strips, two swivel bearings which are displaceable in the direction of

the axis of the form cylinder and in which said clamping strips are respectively mounted and about which said clamping strips are respectively rockable in a plane containing the clamping edge of the form cylinder, two swivel plates on which said swivel bearings are respectively arranged, two sliding plates respectively hinged to said swivel plates, eccentrics for displacing said sliding plates, and, arranged on the form cylinder, clamping means for regulating the shifting of said swivel plates and the clamping of said metal sheet caused by said shifting.

7. A device for fixing metal sheets on offset machines, comprising two clamping strips adapted to have a metal sheet fixed thereto, said metal sheet being displaceable on the form cylinder by shifting said clamping strips, two swivel bearings which are displaceable in the direction of the axis of the form cylinder and in which said clamping strips are respectively mounted and about which said clamping strips are respectively rockable in a plane containing the clamping edge of the form cylinder, two swivel plates on which said swivel bearings are respectively arranged, two sliding plates respectively hinged to said swivel plates, eccentrics for displacing said sliding plates, and, arranged on the form cylinder, a clamping device for regulating the shifting of said swivel plates and the clamping of said metal sheet caused by said shifting, said clamping device being common to said two swivel bearings.

8. A device for stretching flexible sheets on the form cylinder of offset machines comprising clamping strips provided for tightening and loosening said sheets, swivel bearings arranged transversely to the axis of the form cylinder for swinging said strips, whereby on displacement of the axis of the form cylinder of the offset machine angle displacements of a flexible sheet may be counterbalanced, a lever on which each swivel bearing is mounted, a sliding piece displaceable in the direction of the axis of the form cylinder for guiding each lever and by the shifting of which the tightening or loosening of the sheets is facilitated and eccentrics engaging said sliding pieces for causing a displacement of said sliding pieces.
